UNITED STATES PATENT OFFICE.

WILLIAM A. BISHOP, OF NEW LONDON, WISCONSIN, ASSIGNOR TO THE WISCONSIN CHAIR COMPANY, OF PORT WASHINGTON, WISCONSIN, A CORPORATION OF WISCONSIN.

THEATER-CHAIR HINGE.

1,262,596.

Specification of Letters Patent.

Patented Apr. 9, 1918.

Application filed January 18, 1915. Serial No. 2,805.

To all whom it may concern:

Be it known that I, WILLIAM A. BISHOP, a citizen of the United States, and resident of New London, in the county of Waupaca and 5 State of Wisconsin, have invented new and useful Improvements in Theater-Chair Hinges, of which the following is a description, reference being had to the accompanying drawings, which are a part of this specification.

This invention relates to improvements in theater chair hinges more particularly adapted for connecting the chair seats or bottoms to the side members or standards.

15 In many theaters and public halls the chairs are arranged in curved or angular formation and in which formation the side standards of the chairs are not parallel with relation to each other and it has heretofore been somewhat difficult to adjust the chairs so that their hinged bottom portions may be easily swung upwardly and downwardly without undue friction and noise.

It is one of the objects of the present invention to overcome the before mentioned 25 objectionable features and provide a theater chair hinge which is adapted to connect the chair seat or bottom to the side members or standards in such a manner as to permit 30 the free movement of the seat portion whether or not the side standards are in parallel relation.

A further object of the invention is to provide a theater chair hinge which may be 35 adjusted without separating the parts to compensate for wear.

A further object of the invention is to provide a theater chair hinge having means for cushioning the blow of striking parts when 40 the chair bottom is swung to its upper or lower positions to eliminate the noise and to prevent undue strain of the parts.

A further object of the invention is to provide a theater chair hinge which may be 45 stamped and formed of sheet material.

A further object of the invention is to provide a theater chair hinge which is of simple construction, is easily assembled and is well adapted for the purpose desired.

With the above and other objects in view the invention consists of the improved theater chair hinge and its parts and combinations as set forth in the claims, and all 55 equivalents thereof.

In the accompanying drawing in which the same reference characters indicate the same parts in all of the views:

Figure 1 is a central vertical view of a theater chair provided with one of the improved hinges connecting the bottom portion to the standards, the standard and chair back being indicated by dotted lines;

Fig. 2 is a vertical sectional view of the hinge taken on line 2—2 of Fig. 1;

Fig. 3 is a vertical sectional view taken on line 3—3 of Fig. 2; and

Fig. 4 is a horizontal sectional detail view taken on line 4—4 of Fig. 2.

Referring to the drawing the numeral 5 indicates a chair standard, 6 the back, 7 the seat and 8 the seat braces which are hinged to the standards by the improved hinges 9 (only one standard, brace and hinge being shown). Each seat brace 8 is stamped and 70 formed of sheet metal and at the axis of its movement is provided with a circular reinforcing plate 10 which is riveted to the inner side of the brace member by rivets 11. Both the brace 8 and the plate 10 are embossed 80 outwardly to form a ball or spherical portion 12 which is in alignment with the axis of movement of the chair seat.

An offset bracket 13 riveted to the side of the standard 5 is provided with a part 85 spherical recess or socket 14 formed therein into which the embossed portion of the seat brace 8 closely fits. The embossed portion of the reinforcing plate 10 fits into the part 90 spherical recess or socket 15 of the angular clamping member 16 which is adjustably connected to the bracket 13 by the clamping screw 17 and the headed angular portion 18 of the said clamping member 16. The headed end portion 18 of the clamping member 95 is bent at right angles to the recessed portion thereof and extends through a T-shaped opening 19 provided in the bracket 13. The portion of the opening 19 nearest to the part 100 spherical recess 14 is of sufficient width to permit the passage therethrough of the headed end portion 18 while the outer or stem portion of the opening is of a less width than the headed end so that when the 105 said headed end is passed through the opening and the clamping member is moved outwardly from the recess 14 the said head will be hinged and removably locked to the bracket. The opposite end of the clamping member is provided with an opening 20 110

through which the clamping screw 17 extends. The screw also extends through the elongated concentric slot 21 formed in the seat brace 8 and the reinforcing plate 10 5 and through an opening 22 in the bracket 13 and on its threaded end is provided with a nut 17' which bears against the outer side of the bracket and is prevented from turning by the shoulder 13' formed on the bracket 13 so that by turning the head of the screw beneath the chair seat the spherical portion of the seat bracket may be adjustably clamped between the bracket and the clamping member. This construction 10 forms ball and socket connections between the seat and the standards and permits the seat to be freely swung upwardly and downwardly whether or not the two standards, between which the seat is mounted, are in 15 parallel relation.

The clamping screw 17 has a split anti-friction roller 23 journaled thereon which travels in the concentric slot 21 and the medial portion of the said slot is of sufficient width to permit the free turning of 25 said roller, whereas the portion 21' of the slot adjacent its opposite ends are of less width than the diameter of the roller so that said roller will be clamped and held 30 between the edges of the bracket forming the slot before the roller strikes against the end edges of the slotted portion of the bracket. This stop engagement of the roller with the bracket limits the movement of the 35 seat portion from its lower seating position to its upper folded position and as the ends of the roller formed by the split portion are spaced a slight distance apart the stop engagement is cushioned by the yielding of the 40 roller due to its compressibility.

It will be noted that the split 23' of the roller extends obliquely to its axis of rotation in order to permit a lateral movement of the split end portions if the roller is 45 pressed to the point where its ends abut thereby eliminating a pound. The oblique split also serves to eliminate a flat portion which is always present with split rollers having the split extending parallel to their 50 axis.

It will also be noted that the clamping member 16 and the bracket 13 are spaced from the flat portion of the seat brace a sufficient distance to permit limited universal movement of said seat brace without 55 striking the parts.

Portions of the bracket and the reinforcing plate are cut away to accommodate the angular portion 18 of the clamping 60 member 16 and to form stop shoulders 24 which serve to positively limit the movement of the chair seat in the event of undue wear of roller or the edges of the bracket forming the slot.

65 The clamping member is formed with re-

inforcing flanges 25 for bracing said member.

While only one hinge has been described and shown it is to be understood that each seat is to be placed between a pair of standards and to be connected thereto by two hinges and also that in inside seats, each standard is to have a seat hinged to each side thereof. It is to be understood that while the hinge is shown as being particularly adapted for use in connection with a theater chair it may also be used in connection with other chairs having hinged seats.

From the foregoing description it will be seen that the theater chair hinge is of simple construction and is well adapted for the purpose described.

What I claim as my invention is:

1. A chair hinge, comprising a chair member provided with a part spherical recess and with a T-shaped opening, an angular clamping member having a T-shaped end which enters the chair member opening and lockingly engages the chair member, said clamping member having a portion spaced from the chair member which is provided with a spherical recess registering with the recess of the chair member, a seat member interposed between the chair member and the spaced portion of the clamping member and having part spherical projections which enter the registering recesses, said seat member having an elongated opening approximately concentric with relation to the axis of the recesses, the end portions of said elongated opening being of less width than the medial portion, a clamping screw extending through the elongated opening and engaging the chair member and the free end portion of the clamping member, and a roller journaled on the screw and positioned to travel in the elongated concentric opening and to engage the portions of the seat member forming the narrow portions of the elongated opening.

2. A chair hinge, comprising a chair member having a part spherical recess pressed inwardly therein and also having a T-shaped opening, an angular clamping member having a T-shaped end which lockingly enters the T-shaped opening, said clamping member having a portion spaced from the chair member which is provided with a pressed part spherical recess registering with the recess of the chair member, a seat member having a portion interposed between the chair member and the spaced portion of the clamping member and said portion provided with a reinforcing plate, said interposed portion and said plate having outwardly bulged portions of part spherical shape which bear in the part spherical recesses, said interposed portion and the reinforcing plate provided with an elongated opening ap-

proximately concentric with relation to the axis of the recesses, the end portions of said elongated opening being of less width than the medial portion, a clamping screw extending through the elongated opening and engaging the chair member and the free end portion of the clamping member, and a split roller journaled on the screw and positioned to travel in the elongated concentric opening 10 and to engage the portions of the seat member forming the narrow portions of the elongated opening.

3. A chair construction, comprising a chair member, a seat member hinged thereto and provided with an elongated opening concentric with relation to the movement of the seat, the opposite end portions of the opening being of less width than the medial portion, and a yielding roller journaled on the chair member and entering the opening and adapted to engage the portions of the seat member forming the narrow portions of the elongated opening.

4. A stop mechanism, comprising two members pivotally connected together, one of said members having an elongated con-

centric opening, the opposite end portions of said opening being of less width than the medial portion, and a split yielding roller journaled on one of the members and extending through the elongated opening and adapted to be engaged and compressed between the edge portions of the member forming the narrow portions of the opening.

5. A stop mechanism, comprising two members pivotally connected together, one of said members having an elongated concentric opening, the opposite end portions of said opening being of less width than the medial portion, and an obliquely split yielding roller journaled on one of the members and extending through the elongated opening and adapted to be engaged and compressed between the edge portions of the member forming the narrow portions of the opening.

In testimony whereof I affix my signature in presence of two witnesses.

WILLIAM A. BISHOP.
